US00D863705S

(12) **United States Design Patent** (10) Patent No.: **US D863,705 S**
(45) Date of Patent: **** Oct. 15, 2019**

(54) **CLEANING DEVICE FOR SOLDERING TIPS**

(71) Applicant: **Guangzhou Yihua Electronic Equipment Co., Ltd.**, Guangzhou, Guangdong (CN)

(72) Inventor: **Mingkang Gou**, Guangdong (CN)

(73) Assignee: **GUANGZHOU YIHUA ELECTRONIC EQUIPMENT CO., LTD.**, Guangzhou, Guangdong (CN)

(**) Term: **15 Years**

(21) Appl. No.: **29/606,252**

(22) Filed: **Jun. 2, 2017**

(30) **Foreign Application Priority Data**

Dec. 8, 2016 (EP) 003507268-0018

(51) LOC (12) Cl. **07-05**

(52) U.S. Cl.

USPC **D32/35**

(58) **Field of Classification Search**

USPC D32/1, 35; D8/14, 30, 71, 90; D9/504, D9/526, 529; D19/77, 84, 85; D28/73-76

CPC A46B 5/0012; A47L 11/12; B08B 1/04

(57) **CLAIM**

The ornamental design for a cleaning device for soldering tips, as shown and described.

DESCRIPTION

FIG. 1 is a perspective view of the cleaning device for soldering tips.

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets

FIG. 1

FIG. 2

FIG. 3

FIG. 4

FIG. 5

FIG. 6

FIG. 7
